UNITED STATES PATENT OFFICE.

ROSS E. MILES, OF MERETA, TEXAS.

PUMP-FILTER.

1,079,875.

Specification of Letters Patent.

Patented Nov. 25, 1913.

Application filed July 19, 1912. Serial No. 710,470.

To all whom it may concern:

Be it known that I, Ross E. MILES, a citizen of the United States, residing at Mereta, in the county of Tom Green and State of 5 Texas, have invented new and useful Improvements in Pump-Filters, of which the following is a specification.

This invention relates to improvements in pumps and has particular application to 10 filters for pumps.

In carrying out the present invention it is my purpose to provide a filter, whereby oil, dirt, dust and other foreign matter will be prevented from traversing the fluid 15 conducting tube leading from the pump, thereby enabling the air to be forced out of the pump and into a vehicle tire or the like, in a clean state.

Furthermore, I aim to provide a filter 20 which will receive the fluid subsequent to the same being acted upon by the piston of the pump and which will effectively retain the oil and prevent the passage of the same from the pump.

25 A further object of my invention is the provision of a filter which will embrace in its construction the desired features of simplicity, efficiency and durability and one which may be manufactured and marketed 30 at a relatively low cost, and furthermore, my filter may be attached to any style of pump without materially changing or affecting the structure.

With the above recited objects in view and 35 others of a similar nature the invention consists in the construction, combination and arrangement of parts hereinafter set forth in and falling within the scope of the claim.

In the accompanying drawing, the figure 40 is a vertical central sectional view through a pump equipped with the present invention.

In the present instance, I have shown my invention as applied to a double acting air pump. It is to be understood, however, that 45 the invention in its useful application is not limited to any particular type or style of pump, as the same is equally applicable to pumps utilized for pumping other fluids, such, for instance, as gas, and the like and 50 of the single acting type.

Referring now to the accompanying drawing in detail, the numeral 1 indicates the body or cylinder of the pump having the opposite ends thereof opened. A suitable 55 base 2 formed with an air chamber 3 having a relatively large aperture 4 therein is de-

signed to receive one end of the pump cylinder 1 and is further provided with a valve air inlet 5 and a valve outlet 6. Threaded onto or otherwise fastened to the free end of the pump cylinder 1 is a head 7 provided with a valve air intake port 8 and a similar outlet port 9, said head being further formed with an aperture co-axial with the pump cylinder and carrying a stuffing box 10 through which latter is passed the piston rod 11 carrying the piston 12 adapted to be reciprocated within the pump cylinder 1 under the action of the piston rod.

The pump herein described and illustrated 70 is of the double acting type and the operation thereof is substantially as follows: On the up stroke of the piston 12 under the action of the piston rod 11, the intake valve in the passage 5 opens, while the outlet valve 75 in the passage 6 closes, thereby enabling the air to be drawn into the pump cylinder. Simultaneously with this operation the air inlet valve in the port 8 at the opposite end of the cylinder closes, while the outlet valve 80 in the port 9 opens, thus enabling the air, previously drawn into the cylinder through the air inlet port 8 on the down stroke of the piston, to be forced out of the same by way of the outlet port 9, the down stroke of 85 the piston closing the valve in the air intake 5 and forcing the air out of the cylinder by way of the outlet 6.

The filter, in the present instance, is arranged parallel with the cylinder 1 and 90 consists of a tube or cylinder 13 of relatively small diameter as compared with the similar dimension of the cylinder 1 and has the opposite ends thereof threaded or otherwise fastened into the air chamber 3 and the head 95 7 and is in communication with the cylinder 1 by way of the exhaust valves in the passages or ports 6 and 9 respectively, of the air chamber and the head. Mounted within each end of the tube 13 and surrounding the respective outlet passage of the cylinder 1, is a screen 14 constructed of any suitable material and designed to strain or filter the air as the same leaves the pump cylinder to minimize the passage of oil and 100 other foreign matter from the pump cylinder with the air. Extending into the cylinder 13 and terminating approximately centrally of the length of such cylinder, is an air conducting pipe 15 of relatively small 105 diameter, the free end of such pipe being passed through the stuffing box 16 at the

respective end of the tube or cylinder 13 and having connections with an air hose 17, the free ends of the air hose being provided with a suitable nipple whereby the same 5 may be connected to a tire for the inflation thereof.

From the foregoing description taken in connection with the accompanying drawing, the construction and manner of employing 10 my invention will be readily apparent. As the air leaves the cylinder through one or the other of the exhaust passages, oil and other foreign matter, is, to a certain extent, extracted therefrom by means of the screens 15 14, the air subsequently passing from the tube 13 and conducting pipe 15, any oil that may have entered the filter, being deposited therein and settling at the bottom thereof.

While I have herein shown and described 20 one particular embodiment of my invention by way of illustration, it is to be understood that I do not confine or limit myself to all the precise details of construction herein described and delineated, as modifications and 25 variations may be made within the scope of

the claim without departing from the spirit of the invention.

I claim:

In a pump, a cylinder having a piston adapted for reciprocation therein, a filter comprising a tube parallel with said cylinder and of relatively small diameter, screens at the opposite ends of said tube, a base connected to the lower ends of said cylinder and tube and supporting the same and common thereto, and a head connected to the upper ends of said cylinder and tube and common thereto, said base and head carrying the discharge valves of said pump and serving to establish communication between the exhaust side of said cylinder and tube whereby the air delivered from the pump cylinder will be filtered.

In testimony whereof I affix my signature in presence of two witnesses.

ROSS E. MILES.
